EVAPORATORS FOR REFRIGERATION

James A. Hall, Detroit, Mich., assignor to Reynolds Metals Company, Richmond, Va., a corporation of Delaware

Application July 30, 1958, Serial No. 752,144

2 Claims. (Cl. 62—516)

This invention relates to a refrigeration evaporator of the compartment type commonly employed in household refrigerators. The present invention is a continuation-in-part of my copending application Serial No. 434,560, filed June 4, 1954, now abandoned.

The object of this invention is to provide a compartment-type evaporator which is relatively inexpensive to construct and highly efficient and trouble free in operation.

In accomplishing this object of the invention, I start with an expanded passageway panel of any suitable type, preferably the roll bonded type exemplified by the long U.S. Patent #2,662,273, bend it into a tunnel-like structure which is open at its front end (or at both ends), and which otherwise has a top wall, opposite side walls integral with the top wall and a bottom wall. However, before forming the panel, I lay out the passageway system on the original panel blanks in a manner such that the completed panel will have a plurality of serially connected accumulator chambers or pockets with alternate pockets located in opposite side walls of the structure and with the serial conduit connections therebetween extending across the top wall of the compartment structure. The pockets are made large enough to be capable of trapping and holding a substantial quantity of liquid refrigerant during normal evaporator operation. Preferably successive pockets progressively increase in size.

The invention is illustrated in the accompanying drawings, wherein:

Fig. 1 is a perspective view of an embodiment looking at the top and one side thereof;

Fig. 2 is a perspective view showing the opposite side and top of the embodiment shown in Fig. 1;

Fig. 3 is a plan view of the flat blank, formed with flow passages, a grid of evaporator passages, and accumulator pockets, the transverse dotted lines indicating fold lines;

Fig. 4 is a bottom view of the structure shown in Figs. 1 and 2; and

Fig. 5 is an enlarged sectional view taken on the line 5—5 of Fig. 4.

Referring to Figs. 3 and 5, it will be understood that the passageway panel structure is preferably formed of two sheets of metal, preferably aluminum, which are bonded or welded together in face-to-face relation except at areas which define the flow tubes and accumulator wells. Thus, in Fig. 5, a tube shown at 1 is provided by bulging one of the two sheets, which have been bonded together in face-to-face relation, at all areas except at the required tubular areas, the areas of bond virtually forming an integral metallic body. In Fig. 5, the dotted line at 2 indicates the normal division line between the sheets, but this line disappears when roll bonding or pressure welding is employed to unite the two sheets, into an integral structure. Before the roll bonding of the two sheets, there is applied to the face of one sheet, or to the corresponding faces of both sheets, a pattern of a suitable resist, this pattern, in the embodiment shown, defining

2

the tube and the accumulator pocket areas illustrated in Fig. 3.

The resist applied to form said pattern may be molybdenum disulfide and colloidal graphite, the graphite being held in a resin binder, or any other resist having equivalent function, may be applied. The pattern may be applied by silk screen printing, by gravure, or otherwise. In the roll bonding, a substantial reduction in thickness of the sheets is effected, and a suitable roll bonding method is described in the copending application of Jesse B. Thomas and James A. Hall, filed April 27, 1954, Serial No. 425,926, and in the U.S. Patent No. 2,662,273 to Long, issued Dec. 15, 1953.

Referring particularly to Fig. 3, when the blank is bent to form the refrigerator compartment, the area of the plate or panel between the dotted lines 3 and 4 constitute the top wall of the compartment, the area between the dotted lines 5 and 6 constitutes the bottom wall of the compartment, the areas at 7 and 8 which are lapped and secured together form one side wall of the compartment (the left side wall as seen in Figs. 1 and 2), and the area at 9a forms the opposite side wall of the compartment.

Reference to Figs. 1, 2 and 4 in relation to Fig. 3 will show that in the illustrated embodiment the refrigerant liquid introduced at inlet 9 flows upwardly into the parallel tubes 10 which extend upwardly of the side wall, then across the top wall of the box or compartment C, thence downwardly at 11 on the opposite side wall of the box, and thence at 12 transversely of the box bottom, the refrigerant entering a short tubular lead at 13 and thence passing into the grid of refrigerant passages 14 which covers the major area of the said bottom.

Refrigerant flows through the grid of passages 14 along the bottom toward the side of the box shown in Fig. 4, and thence upwardly through a short tubular conduit 15 which leads to the parallel conduits 16, the latter conduits discharging the refrigerant into the first accumulator pocket 17. The accumulator pocket 17 feeds through the tubular conduits 18 to the accumulator pocket 19, the latter feeding through the conduits 20 to the accumulator pocket 21, the latter feeding through the conduits 22 to the accumulator pocket 23, and the latter discharging to outlet 25 by means of the tubular conduits 24.

From the foregoing and particularly from an inspection of Figs. 1-3, it will be seen that the accumulator means comprises a succession of four accumulator chambers or pockets (17, 19, 21 and 23) enclosed within the side walls (defined in one side by areas 7 and 8 and on the opposite side by area 9a). These accumulator pockets are disposed in a fashion such that, proceeding in the direction of refrigerant flow, every other pocket (17, 21) of the succession, beginning with the first, is located on one side wall while each remaining pocket (19, 23) of the succession, beginning with the second, is located on the other side wall. Each of said pockets has a refrigerant inlet and a horizontally spaced outlet in its top. These accumulator pockets are connected in series within the refrigerant passageway system by interposed elongated conduits (16, 18, 20 and 22) which, from the first to the last of said succession, extend across the top wall (the area between dotted lines 3 and 4) and follow a pattern such that the outlet of the first pocket 17 on one side wall is connected by top wall conduits 18 to the inlet of the second pocket 19 on the other side wall while the outlet of the second pocket is connected by conduits 20 to the inlet of the third pocket 21 on said one side wall, the outlet of the third pocket being connected by the top wall conduits 22 to the inlet of the fourth and last pocket 23. The maximum horizontal width of each accumulator pocket, in the direction of the thickness of the panel, is substantially the same as the maximum width (in the

panel-thickness direction) of the elongate conduits crossing the top wall. The maximum length of each accumulator pocket, in a horizontal direction at right angles to its horizontal width, is at least as great as the widest horizontal spacing between the centers of its inlet and outlet openings. Thus, for example, the maximum length of the accumulator pocket 17, in a horizontal direction proceeding at right angles to its horizontal width, is slightly greater than the horizontal spacing between the centers of its outermost inlet opening to which the conduit 16 is connected and its outermost outlet opening to which the conduit 18 is connected. The maximum vertical depth of each pocket is obviously equal to at least 3 times its width. The horizontal width and length and the vertical depth of each pocket being as above defined, the volumetric capacity of each pocket necessarily is several times larger than the volume of the inlet conduits discharging into it over a corresponding length of such conduits. As a consequence, each pocket is capable of trapping and holding a substantial quantity of liquid refrigerant during normal evaporator operation.

It will be seen that the accumulator pockets are more or less symmetrically arranged at the opposite sides of the evaporator box. In operation, in some cases, liquid refrigerant may not be evaporated entirely in the bottom grid 14, tubes 15, 16, or preceding tubes 10 to 13, and the vapor and liquid refrigerant flows into the accumulator pocket 17 which traps the liquid and allows the vapor to continue its movement into the tubes 18. Any overflow of liquid in the accumulator pocket 17 is carried or pushed by the vapor into the accumulator pocket 19, and similarly, any overflow of liquid in the accumulator pockets 19 or 21, is carried or pushed by the vapor into the accumulator pocket 23. The amount of liquid refrigerant which reaches the various accumulator pockets varies, depending on operating conditions, such as, for example, the external atmospheric temperature, the interior temperature, or the heat removal requirements, and the liquid refrigerant level or overflow at the various accumulator pockets thus will vary. Thus, for example, under some conditions, the pocket 23 may be devoid of liquid refrigerant; or the pockets 23, 21 may be empty or partly filled with liquid refrigerant; or the pockets 23, 21 and 19 may be empty or partly filled. Evaporation which occurs in these pockets aids in producing the desired low temperature in the compartment, and these pockets also assist in separating liquid refrigerant from vapor so that the vapor discharged at outlet 25 is more or less superheated. The accumulator pockets 17, 19, 21 and 23 may have equal capacity, or some of the pockets following the first pocket 17 may have greater capacity. In Fig. 3, the pockets 19 and 21 are larger than the pocket 17 while the last pocket 23 is larger than pockets 19 and 21. When the accumulator pocket 17 overflows, continued refrigeration by evaporation action occurs in the conduits 18. When there is sufficient refrigerant to fill the accumulator pocket 19, and this pocket overflows, continued refrigeration by evaporation action occurs in the conduits 20, and likewise, when the pocket 21 overflows, refrigeration by evaporation occurs in the tubes leading to and from the last accumulator pocket 23.

The grid 14 of evaporator tubes is fed by the tubular conduits 9, 10, 11 and 12 at the front of the box, which makes that front area remain cold even when warm air is admitted by repeated opening of the refrigerator door. The greater capacity of the accumulator pocket 23, as illustrated, is to insure that little, if any, liquid refrigerant will go beyond the tubes 24.

While it is preferred that the evaporator blank be formed by roll bonding or pressure welding the two sheets, with resist therebetween at the tubular conduit areas, the grid, and the accumulator pockets, the evaporator blank alternatively may be constructed by die-forming one or both of the two sheets with bulging conduits, grid and

pockets and then brazing or press welding the two sheets together.

While I prefer the use of parallel tubular conduits 10 leading to a single inlet 13 for the grid 14 and parallel conduits 16, 24 leading to and from the accumulator pockets, a single enlarged conduit may be used in each case, if desired. Also, the parallel pairs of conduits 18, 20 and 22 may be replaced by single conduits of appropriate dimensions.

10 In Fig. 5, I have shown tubular expansions at only one face of the structure, but the area opposite thereto may be likewise expanded. Thus, when two aluminum sheets are bonded together, both sheets may be expanded at the tubular and accumulator pocket areas.

15 I prefer that the walls of the accumulator pockets be reinforced by uniting the two sheets within the margins of the pockets in a "waffle-like" pattern of welded areas, as indicated in the drawing.

Having described my invention, I claim:

- 20 1. A refrigeration evaporator comprising: a hollow structure open at the front and composed of a passageway panel constructed of at least two superposed metal sheets bonded together in face-to-face relationship and having a bulged refrigerant-passageway system of unwelded areas 25 between them including accumulator means; said structure having a top wall, opposite side walls integral with said top wall and a bottom wall; said accumulator means comprising a succession of at least three accumulator pockets enclosed within said side walls and disposed in a 30 fashion such that, proceeding in the direction of refrigerant flow, every other pocket of the succession, beginning with the first, is located on one side wall while each remaining pocket of the succession, such as the second, is located on the other side wall, each of said 35 pockets having a refrigerant inlet and a horizontally spaced outlet at its top; said accumulator pockets being connected in series within said refrigerant-passageway system by interposed elongate conduits which, from the first to the last of said succession of pockets, extend 40 across said top wall following a pattern such that the outlet of the first pocket on one side wall is connected to the inlet of the second pocket on the other side wall while the outlet of said second pocket is connected to the inlet of the third pocket on said one side wall; the maximum 45 horizontal width of each accumulator pocket, in the direction of the thickness of the panel, being substantially the same as the maximum width of said interposed elongate conduits in the panel-thickness direction; the maximum length of each accumulator pocket, in a horizontal direction proceeding at right angles to its horizontal width, being at least as great as the widest horizontal spacing between the centers of its inlet and outlet openings, and the maximum vertical depth of each pocket being equal to at least three times its width; and the volumetric capacity of each pocket being several 50 times larger than the volume of a corresponding length of the inlet conduits discharging into it so as to render it capable of trapping and holding a substantial quantity of liquid refrigerant during normal evaporator operation.
- 55 2. The evaporator of claim 1 wherein: the volumetric capacities of said pockets, proceeding in the direction of refrigerant flow, increases from a first pocket of minimum capacity to a last pocket of maximum capacity.
